UNITED STATES PATENT OFFICE

THOMAS J. SOTH, OF BROOKLYN, NEW YORK

PROPORTIONING DRAFTING INSTRUMENT

Application filed January 20, 1928. Serial No. 248,039.

This invention relates to a new and useful device in the nature of a drafting instrument especially adapted for the purpose of providing a means of assisting in the drafting or drawing of objects, scenery, maps and the like, and particularly perspective drawings.

The object of the invention is to provide a device of the class described of novel construction and arrangement of parts, embodying certain adjustable features hereinafter more fully described, claimed and illustrated in the accompanying drawing.

Fig. 1 is a perspective view of my improved device as same would appear when in use.

Fig. 2 is a detail front elevational view of the layout frame as embodied in my improved device.

Fig. 3 is an enlarged detail front elevational view of the drawing frame as embodied in my improved device.

Fig. 4 is a similar view to that shown in Fig. 3 illustrating another form of the drawing frame.

Fig. 5 is a transverse sectional view taken on the line 5—5 of Fig. 4.

As here embodied my improved device comprises a standard 10, or support with a base element 11, of suitable size and weight to support my improved device. The standard 10 is vertically disposed and is provided with an enlarged extended extremity 12, having formed therein a horizontal aperture adapted to slidably receive the rod 13, as a means of horizontally supporting the rod 13. The thumb screw 14 is threadedly mounted in the enlarged extremity 12 of the said standard and is adapted to frictionally engage the rod 13, as a means of holding the said rod in any desired horizontal extended position. The rod 13 is provided with an enlarged extremity 15 having formed therein vertical apertures adapted to slidably receive the stem 16 of the sight 17. The sight 17 is of circular convex construction, having formed therein a central aperture 18. The thumb screw 19 is threadedly mounted in the enlarged extremity 15 of the rod 13, and is adapted to frictionally engage the stem 16 of the said sight, as a means of holding the said

sight in any desired vertically extended position.

The drawing frame 20 is of rectangular frame like construction and is adapted to frictionally engage in an opening 21 formed in the support 22, of block shape construction, having formed therein an aperture adapted to slidably engage on the above mentioned rod 13. The thumb screw 23 is threadedly mounted in the support 22 and is adapted to frictionally engage the rod 13, as a means of holding the drawing frame 20 in any desired vertically extended position in the said rod. The drawing frame 20 has formed therein apertures 24, 25 and 26, 27 positioned or located at the top and bottom and at the two sides thereof, respectively. The flexible member 28, thread, string, cord or the like, is threaded or passed through the said apertures formed in the drawing frame 20, so as to provide transverse and longitudinal members 29 and 30 extended across the opening formed in the said drawing frame.

My improved device is used as follows:— the drawing frame supported as above set forth in place in front of the object desired to be drawn, the person making the drawing looks through the aperture formed in the sight for the purpose of permitting the said transverse and longitudinal members extended across the opening formed in the drawing frame to provide guide lines which will obviously assist in the drawing of the said object.

In Fig. 2 of the accompanying drawing, I have shown a layout frame 31, of rectangular frame shape construction, having formed therein apertures 32, 33, 34 and 35 formed in the top, bottom and sides, respectively thereof. The above described construction is such as will permit the layout frame to be placed on the piece of paper upon which the above mentioned drawing is to be made, and a pencil point inserted through, for the purpose of providing guide dots on the said piece of paper which will permit transverse and longitudinal lines to be drawn on the said piece of paper, which will obviously assist in the drawing of the said object on the paper.

In Figs. 4 and 5, I have shown a drawing frame 36, substantially of rectangular frame shaped construction, provided with an arc shaped side 37, formed at a radius from the pin 38, secured to and extended from the opposite side of the said drawing frame 36, and provided with a similar arc shaped top 39, formed at a radius from the pin 40, secured to and extended from the bottom of the said drawing frame. The flexible members 41 and 42 are secured respectively, to the pins 38 and 40, and are extended therefrom and are secured respectively to the extended elements 43 and 44, respectively, of the clamp members 45 and 46, provided with lower extended elements 47 and 48, adapted to frictionally engage the arc shape side and top, respectively of the said drawing frame. The said clamp members 45 and 46 are provided respectively with handle elements 49 and 50, as a means of slidably positioning the said clamp members as may be desired, and designated by the reference numerals 51, 52, 53 and 54, respectively. The drawing frame has affixed thereto, graduation marks 55 and 56 with accompanying and corresponding degrees affixed thereto, as a means of designating the angularity of the said flexible members. The above described construction is such as will obviously assist in the drawing or reproduction of objects in perspective.

Having thus described my invention, what I claim as new and desire to protect by United States Letters Patent is:—

35. In a drafting instrument of the class described, a drawing frame provided with an arcuate side and top, a cord secured at one end on the bottom of the frame and at the center of curvature of said arcuate top, a 40 second cord secured at one end on the side of the frame opposite the said arcuate side at the center of curvature of said side, clamp members slidably mounted on the arcuate top and side of said frame, and the other ends 45 of the cords being attached on the clamp members respectively for providing guide lines.

In testimony whereof I have affixed my signature.

50 THOMAS J. SOTH.
